UNITED STATES PATENT OFFICE.

EDWIN C. MILLIKEN, OF PORTLAND, MAINE.

BELT OR GIRDLE SUPPORT.

No. 839,615.

Specification of Letters Patent.

Patented Dec. 25, 1906.

Application filed October 19, 1905. Serial No. 283,427.

To all whom it may concern:

Be it known that I, EDWIN C. MILLIKEN, a citizen of the United States, residing at Portland, in the county of Cumberland and State 5 of Maine, have invented certain new and useful Improvements in Belt or Girdle Supports, of which the following is a specification, reference being had therein to the accompanying drawings.

10 My present invention relates to improvements in a belt or girdle support, and has special reference to a support by means of which a military belt, preferably, is supported evenly by a coat, shirt, or the like 15 worn by the wearer, a simple device being provided which is secured to the coat or shirt in the proper place. To aid this support, the invention consists of a device of the character embodying novel features of construction, as will presently appear.

In the accompanying drawings, Figure 1 is a rear elevation of a coat, showing the belt in the position it assumes when properly supported by my device. Fig. 2 is an enlarged 25 detail view of a portion of the coat, the supporting device, and a portion of the belt. Fig. 3 is an enlarged detail view of the device in elevation, and Fig. 4 is a perspective view of the device carried by the belt.

30 Referring to the drawings, the numeral 1 designates a coat which, as usual, is provided with the seam 2, extending from below the arm to the waist. The belt-supporting device 3 consists of a metal stay or plate 4, 35 which is provided with a series of openings 5, through the body thereof. The upper opening has adapted to pass therethrough a rivet or fastening means 6, which is adapted to engage the seam of the coat, so that the plate 40 will be held concealed or out of view, as shown in Fig. 1 of the drawings. The remaining holes are used for adjusting the knob or button 7, which is provided with a shank 8 to enter one of the openings and with 45 a head 9, which is adapted to enter an opening or buttonhole 10, formed upon the seam of the coat, so that the knob or button will extend exteriorly of the coat to receive the eye 11 of the belt-support 12, which is 50 cured to the belt 13, as clearly shown in Fig.

2 of the drawings. As two of these supporting-plates are used, it will be seen that the belt will be properly supported directly from the shoulders of the wearer and carried entirely by the coat, the belt also being supported in a position so that it will not drag down or touch the hip. By this means a uniformity in appearance is secured, and the necessity of wearing the belt tight is also dispensed with.

55 The extra weight of a sword or a bayonet and scabbard will not have the tendency to drag the belt to one side, the supporting-device being so connected to the coat or shirt as to prevent it sagging. By this means the 60 coat will also be pulled down more smoothly and prevented from wrinkling beneath the belt, and thus render the wearing of a belt 65 more comfortable and attractive.

70 What I claim as new, and desire to secure by Letters Patent, is—

1. In combination with a body-garment, and a belt, of a device for supporting the belt, consisting of a pair of supports secured to the garment and each provided with a series 75 of openings, a knob for each support having a shank adapted to enter the openings of the support one at a time to regulate the height the belt is to be supported, the said knob extending exteriorly of the garment, and a pair 80 of eyed supports carried by the belt adapted to engage the knobs, as set forth.

2. In combination with a body-garment and a belt, of a device for supporting the belt, consisting of a pair of supports secured to the 85 garment and each provided with a series of openings, a knob for each support having a shank adapted to enter the openings of the support one at a time to regulate the height the belt is to be supported, the said knob extending exteriorly of the garment, and means 90 carried by the belt adapted to engage the knob, as set forth.

In testimony whereof I affix my signature in presence of two witnesses.

EDWIN C. MILLIKEN.
